NEUMAN TOBIAS, OF KINGSTON, JAMAICA.

COMBINATION-PADLOCK.

No. 878,913.

Specification of Letters Patent.

Patented Feb. 11, 1908.

Application filed August 13, 1907. Serial No. 388,294.

To all whom it may concern:

Be it known that I, NEUMAN TOBIAS, a subject of the King of Great Britain, residing at Kingston, Jamaica, West Indies, have invented certain new and useful Improvements in Combination-Padlocks, of which the following is a full, clear, and exact description.

My invention relates to combination padlocks, and consists essentially in a padlock having an index plate or disk on its front face, which, when moved in a predetermined manner, actuates interior mechanism of the lock to release the usual keeper or shackle.

In carrying out the present invention, the main purpose in view has been to have all of the functions of the lock accomplished by a single dial plate which has to be moved in an exact predetermined sequence of three successive settings, the lock being responsive to no other movements of the dial of any character whatsoever. Inasmuch as the exact setting of the dial to three successive positions in a proper and exact sequence is very unlikely to be attained accidentally or by trial of an unauthorized person, it is evident that the lock is made adequately secure. But although this complex manipulation is made necessary to open the lock, the interior mechanism thereof is nevertheless extremely simple, compact and strong or durable in construction, so that it is not only applicable to a very neat compact form of padlock, but also one which is very inexpensive to manufacture and not liable to failure or derangement in use.

Additional features of the invention have been the pivoting of the index plate or dial on an axis concentric with the circular body of the padlock, which gives the completed article a very neat and regular appearance.

A combination padlock of this type is specially applicable to many uses where carrying a key is inconvenient, for example, on private bath houses. Also where a large number of parties should have authorized access to something which is locked against the general public. For example, the ice-box in a club-house, and other similar arrangements.

In the drawings, Figure 1 is a side elevation of a combination padlock embodying the principles of my invention. Fig. 2 is a view of the same from the other side, the cover plate being removed. Fig. 3 shows the same in proper relation to release the keeper or shackle. Fig. 4 is a sectional view on the line IV-IV of Fig. 3. Fig. 5 is a

view looking into the casing, certain of the parts being removed. Figs. 6 and 7 are detail views showing certain of the parts.

Referring to the drawings in which like parts are designated by the same reference sign, 1 indicates the main body or casing of the padlock, and 2 the shackle pivoted to the main body at 3. The body 1 is preferably of generally circular outline so as to have a circular interior chamber or cavity 4. The shackle 2 has a terminal double hook portion 5 adapted to enter into the circular chamber 4 through a suitable side opening 6.

Within the body or casing 1, preferably at a point diametrically opposite the opening 6, there are pivoted two levers 7 and 8 on the pivotal studs 9 and 10 respectively. 7^a and 8^a denote springs impelling these levers normally inward. Both of these levers are made curved into a generally semi-circular shape conforming to the curvature of the wall of the casing 1. At the ends, both levers have bent-over or hook-shaped portions 11 adapted to engage the respective prongs of the double hook 5 of the shackle. The combination lock mechanism is adapted to coöperate with these levers 7 and 8 to displace them outward, and thereby release the shackle when the settings of the combination are properly made. For this purpose, there is provided a rigid member 12 with a dial portion 12', and a cylindrical portion 12'', which last-named cylindrical portion fits in a hole in the front wall of the casing 1, so as to turn freely therein. The center of this hole is concentric with the periphery of the cylindrical casing 1.

13 and 13' indicate semi-circular plates constituting parts of a split washer inserted in a groove 12^a in the member 12 so as to hold this member in proper rotatable relation in, but secured against withdrawal from, the body or casing 1. The rigid member 12 carries two entirely separate concentrically mounted elements 14 and 15. 14 is a ring having an internally projecting tooth 16 thereon (see particularly Fig. 7), and this ring surrounds a portion of the member 12 which is exteriorly toothed around its entire circumference as shown at 16' in Fig. 5. By virtue of this construction, the ring 14 may be positioned in any predetermined angular relation upon the member 12, in which position it is thereupon locked by the intermeshing engagement of the tooth 16 with the teeth 16'. This ring carries a detent later

described adapted to coöperate with the pivoted lever 8 in the unlocking operation, as will later appear.

The part or element 15 is freely pivoted on a reduced portion 12⁴ of the member 12, and is conveniently held in such relation by a screw 17. This part 15 therefore constitutes a freely swinging arm co-axial with the member 12, and has at its extremity an enlargement 15' extending laterally or transversely therefrom. This enlargement 15' presents a narrow rounded edge at its outermost portion or extremity, extending parallel to the axis of revolution of the member 12.

15 18 designates a detent pivoted to the ring 14 at the point 19 and also having a rounded outer edge or extremity 18'. The detent 18, is, however, made substantially straight or unrounded on one side edge or face as shown at 18², the rounding being substantially all on the opposite side as shown at 18³. I arrange the detent 18 to be normally spring-impelled by means of a spring 20 on the ring 14 and which engages the detent. The detent is movable on either side of its central position into which it is spring-impelled, but is capable of being moved in this way a greater distance to one side than toward the other. This is conveniently accomplished 25 by forming a shoulder 18⁴ on the detent which engages the ring 14 after a predetermined movement of the detent in either direction from its central or radial position. As shown in Fig. 7, the detent is movable upward or away from the rounded side 18³ to a greater distance than it is movable downward or away from the flat or straight edge 18².

I make the radial length of the arm 15 from 40 the center to its rounded portion or extremity slightly less than the radial distance from the center of the ring 14 to the rounded extremity 18' of the detent 18. Upon the internal faces of the levers 7 and 8 there are 45 lugs or protuberances 7' and 8' of which 7' extends inward toward the axis or member 12 a greater distance than the lug 8'. Both lugs have a central depression or groove 21. The lug 8' presents no flat faces or corners at 50 any point or in any direction to impede the free passage of either the arm 15 or the detent 18 in a movement past the same. The lug 7' also presents no flat faces or corners to impede the movement of said arm or detent 55 in any direction, except the corner or flat face 21'. 22 designates an additional lug extending inward to a less degree than the lug 7', and about corresponding to the inward elevation of the lug 8'. This lug 22 has a 60 flat face or corner 21" which is capable of engaging the flat face 18² of the detent 18, so as to resist the movement thereof. This lug 22 does not project sufficiently inward to engage the arm 15 under any circumstances, 65 and the same is true of the lug 8'. These

lugs 22 and 8' coöperate solely with the detent 18, while the lug 7' projects sufficiently inward to engage either the detent 18 or the arm 15. The relation of the various parts is such that when the detent 18 is seated in the 70 groove 21 of the lug 8' and the arm 15 has its extremity seated in the groove 21 of the lug 7', as shown in Fig. 3, the levers 7 and 8 will be sufficiently impelled apart or separated to release the shackle 2 of the padlock.

The operation is as follows: Assuming that the parts are in their locked relation as shown in Fig. 2, it is evident that the detent 18 and the arm 15 may be anywhere in the range of their circular movement, but the 80 arm 15 is most likely to hang downward since it is freely pivoted. In order to properly move these parts to release the shackle, it is first necessary to position the arm 15 against the lug 7', and thereafter position the detent 85 18 on the lug 8'. The arm 15 can only be moved by the dial 12' through the intermediate engagement of the detent 18, which accordingly serves the initial purpose of an abutment or crank to propel said arm 15 90 rotatably. If the dial is impelled right-handedly (or anti-clockwise in Fig. 2), the detent 18 will eventually engage the arm 15 and propel said arm in the same anti-clockwise direction until its rounded extremity is 95 brought into the groove 21 of the lug 7'. It is impossible to do this by a clockwise movement of the detent 18 in Fig. 2, because of the arrest of the detent by the lug 22 before it has accomplished this function. If the parts 100 happen to be in the relation of Fig. 2, substantially a single rotation of the dial might be sufficient to make the proper initial setting, but if the parts happen to have a different relation, it might be necessary to make 105 two complete rotations of the dial before an initial setting may be made. It is apparent therefore that at least two continuous revolutions of the dial should be given at the first setting. The arm 15 being properly positioned on the lug 7', it is evident that the lever 7 is displaced to release the shackle, but the lever 8 still remains in its original locking position. If the dial now be given a reverse 110 movement (clockwise in Fig. 2) the detent 18 may be brought beneath the lug 8' and into the groove 21 thereof. In this movement, however, the detent will have swung rearwardly from its central or radial position, so that it does not yet impel the lever 8 sufficiently far to release the shackle 2. In order to obtain such release it is necessary to give the dial a third and final reverse movement, again anti-clockwise in Fig. 2 which has the 115 effect of straightening out the detent 18 into an exact radial position as shown in Fig. 3, in which position it impels the lever 8 far enough outward to freely release the shackle.

As shown in Fig. 3, I make the corners of the double hook 5 and the hooks 11 all bev- 120

eled, so that when the keeper is finally pulled outward, the levers 7 and 8 will be disturbed outwardly a little further, enough to release the engagement of the arm 15 which quickly 5 drops by gravity, so that the shackle may be snapped back into locking position without bothering to rotate the dial. A strict analysis of the above construction and operations will show that it is impossible to achieve the 10 proper unlocking movement of the levers 7 and 8 in any way, except by the exact sequence of movements described, and which calls for three successive settings of the dial. I have illustrated the dial with sixty divisions, and it is feasible to estimate halves or even quarters of these divisions in making 15 settings. There is accordingly only one chance in 13,824,000 that a person unfamiliar with the construction of the lock will accidentally succeed in obtaining the right combination. If a person is familiar with the 20 general nature of the lock, the chances of opening it would, of course, be greater, but as different locks may be manufactured with 25 somewhat different arrangements of the internal parts, left and right-handed, etc., and as each individual lock may have its settings readjusted at any time by displacing the ring 14 on the teeth 16', the probabilities of the 30 lock being opened by any unauthorized person are exceedingly remote.

A feature of the invention lies in the cover 30 which is circular, corresponding to the outline of the body or casing 1. This cover has 35 a bayonet joint connection 31, 31' with the body or casing, and concentric with said body and with the member 12. When the cover is turned so that the bayonet joint is in locking position, it presents an opening 32 in the flange 31 of the bayonet joint, through 40 which the shackle 2 may enter and lock the cover against turning backward to unfasten the bayonet joint until the shackle has been again released by the combination lock.

45 What I claim, is:

1. In a combination padlock having a shackle, a plurality of levers separately engaging the shackle, a plurality of devices all rotatable on a single axis for impelling said

levers to release the shackle, and a single dial 50 movable to position all of said devices whereby the shackle can be released.

2. In a combination padlock having a shackle, means engaging the shackle to hold it in locking relation, a member having a dial, 55 and a detent and a swinging arm both supported by said member and adapted to engage said means to release the shackle.

3. In a combination padlock having a shackle, levers having grooved protuberances 60 and constructed to engage the shackle, and a member carrying separately movable means to engage said protuberances, said means being so positioned by successive movements of the member. 65

4. In a combination padlock having a shackle, levers having lugs or protuberances and adapted to engage the shackle, a member rotatable within the padlock and having a dial, a detent carried by said member and 70 adapted to engage one of said lugs, and an arm freely pivoted on said member and adapted to engage the other lug, whereby the shackle is released.

5. In a combination padlock having a 75 shackle, levers adapted to engage the shackle, a rotatable member, a ring angularly adjustable thereon, a detent pivoted to said ring to swing either side of a radial position thereon, and an arm shorter than the radial distance 80 of the extremity of said detent from the axis of its supporting member, and pivoted on said member co-axially therewith.

6. In a combination padlock having a shackle, means adapted to engage the shackle, 85 a member having a detent, and a swinging arm positioned by said detent, whereby the detent and said arm are adapted to be successively positioned to engage said means and release the shackle by successive movements 90 of said member.

In witness whereof, I subscribe my signature, in the presence of two witnesses.

NEUMAN TOBIAS.
